1 Claim

ABSTRACT OF THE DISCLOSURE

This invention pertains generally to headwear, and particularly to a means for causing the head band to be retained in place on the head. The means includes a piece of material in combination with a headwear, the material having a plurality of resilient hooks projecting outwardly therefrom which are adapted to intertwine with the strands of hair of the wearer when the hooks are pressed into a wearer's hair.

This invention relates to headwear, and more particularly it is an object of this invention to provide a means for causing annular head band to be retained in place on the head.

More particularly it is an object of this invention to provide the concept of utilizing a piece of material having a plurality of projecting hooks, the material being attached to a piece of head band in a manner for engaging in the hairs of the wearer with individual hooks hooked under and partially around individual hairs or units of several hairs of the wearer for providing effective anchorage against displacement, especially displacement from slippage.

A further object of the invention is to provide a concept of utilizing material as described on a head band. Because head bands are formed of stretchable material, they tend to contract after being stretched in place and thereby to slip out of place. It is, therefore, an objective to prevent this slippage by use of a hook-like material which intertwine with the strands of hair of the wearer.

Heretofore head bands have necessarily been very tight fitting to assist them to stay in place. The tightness of the fit can hurt the ears of the wearer. It is, therefore, an object of this invention to provide a head band which can be worn more loose and comfortably.

It is a particular object of the invention to provide means for securing in place any article that would engage the hair of a person.

Other and further objects and advantages of the present invention will be apparent from the following detailed description, drawings and claims, the scope of the invention not being limited to the drawings themselves as the drawings are only for the purpose of illustrating a way in which the principles of this invention can be applied.

In the drawings:

FIGURE 1 is a perspective view of the head band shown in place on a wearer.

2

FIGURE 2 is a side elevation of the head band of FIGURE 1.

FIGURE 3 is a sectional view of the head band of FIGURE 2 as it would be seen along the line 3—3 of FIGURE 2.

5 In FIGURE 1, a headwear assembly is generally shown at 10 and the specific headwear assembly shown comprises a piece of headwear 12 which is more specifically what is commonly known as a head band.

The head band 12 is formed in a conventional fashion of stretchable resilient material and to that extent, it is conventional.

15 However, in accordance with this invention, a piece of material 14 is attached to the underside of the head band 12 in a position such that the resilient hooks 20 which protrude outwardly therefrom are in a position for engaging the hair 26 of a wearer 30.

Each hook 20 is adapted to extend under and partially around one or more of the hairs of the wearer 30 holding the head band 10 firmly in place.

20 The piece of material 14 can be secured to the head band 12 in any suitable manner and cement shown at 36 can be employed, if desired.

25 As thus described, it will be seen that this invention has fulfilled the objectives above set forth in providing a piece of head band which will have a greater tendency to stay in place.

30 From the foregoing description, it is thought to be obvious that a position-holding head band assembly constructed in accordance with my invention is particularly well adapted for use, by reason of the convenience and facility with which it may be assembled and operated, and it will also be obvious that my invention can be changed and modified without departing from the principles and spirit thereof, and for this reason, I do not wish to be understood as limiting myself to the precise arrangement and formation of the several parts herein shown in carrying out my invention in practice, except as claimed.

I claim:

35 1. In combination with a head band, a piece of material having a plurality of resilient hooks extending outwardly therefrom, said hooks being adapted to intertwine with the strands of hair of a wearer when said hooks are pressed into a wearer's hair thus holding said material in place, and means attaching said piece of material to the underside of said head band in a position for engaging the wearer's hair.
